CLAIM

The ornamental design for a launching apparatus for spinning top toy as shown and described.

DESCRIPTION

FIG. 1 is a front elevational view of a launching apparatus for spinning top toy, showing the new design; FIG. 2 is a rear elevational view thereof; FIG. 3 is a left-side elevational view thereof; FIG. 4 is a right-side elevational view thereof; FIG. 5 is a top plan view thereof;

FIG. 6 is a bottom plan view thereof; FIG. 7 is a front, right-side, top perspective view thereof;

FIG. 8 is a front, bottom perspective view thereof;

FIG. 9 is a rear, left-side, top perspective view thereof;

FIG. 10 is rear, left-side, bottom perspective view thereof;

FIG. 11 is a cross-sectional view taken along line 11-11 in FIG. 5;

FIG. 12 is a cross-sectional view taken along line 12-12 in FIG. 5; and,

FIG. 13 is a reference view showing a state of use.

The broken lines depict parts of the launching apparatus for spinning toy that form no part of the claimed design.

1 Claim, 12 Drawing Sheets
